Primary Examiner — David Muller*Assistant Examiner* — Nathan Johnston(74) *Attorney, Agent, or Firm* — Wood Herron & Evans LLP(57) **CLAIM**

The ornamental design for a dispenser, as shown and described.

DESCRIPTION

FIG. 1 is a perspective view of a dispenser showing our new design;

FIG. 2 is a front elevation view thereof;

FIG. 3 is a right side elevation view thereof with the left side elevation view being a mirror image thereof; and,

FIG. 4 is a top plan view thereof.

The features shown in broken lines depict environmental subject matter only and form no part of the claimed design.

1 Claim, 4 Drawing Sheets---
